UNITED STATES PATENT OFFICE

155,271

DESIGN FOR A PAPER DISPENSER

Walter J. Collard and George W. De Loof,
Detroit, Mich.

Application September 17, 1947, Serial No. 141,448

Term of patent 7 years

(Cl. D4—3)

To all whom it may concern:

Be it known that we, Walter J. Collard and George W. De Loof, citizens of the United States, residing at Detroit, in the county of Wayne and State of Michigan, have invented a new, original, and ornamental Design for a Paper Dispenser, of which the following is a specification, reference being had to the accompanying drawing, forming a part thereof, in which:

Fig. 1 is a top plan view of a paper dispenser, embodying our invention; and

Fig. 2 is a front elevational view;

Fig. 3 is an end elevational view; and

Fig. 4 is a view in perspective.

We claim:

The ornamental design for a paper dispenser, substantially as shown.

WALTER J. COLLARD.
GEORGE W. DE LOOF.
